UNITED STATES PATENT OFFICE.

CHARLES BOOZ, OF BUFFALO, NEW YORK, ASSIGNOR TO HENRY M. BIRGE,
OF SAME PLACE.

DESIGN FOR WALL-PAPER.

SPECIFICATION forming part of Design No. 26,130, dated September 29, 1896.

Application filed August 24, 1896. Serial No. 603,788. Term of patent 3 $\frac{1}{2}$ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

- 10 The design consists of an arrangement of large and small ornamental panels formed of small ornamental scrolls and forming the top and bottom of the design and connected by vertical ornamental stripes also formed of 15 small ornamental scrolls and forming the body or center portion of the design between said panels, as represented in the accompanying drawing. The large panels at the top contain a landscape and windmill in the 20 center, and the small panels on each side of

the large panel at the top also contain small landscapes, as shown, while the large and small panels at the bottom of the design contain groups of flowers and leaves, as shown. Small ornamental panels formed of small ornamental scrolls, with flowers and leaves in the center, are arranged in said vertical ornamental stripes, as shown in the drawing, and in the open space between said vertical stripes are small sprays and star-shaped flowers, as shown.

What I claim is—

The design for wall-paper herein shown and described.

Witness my hand this 10th day of August, 1896.

CHARLES BOOZ.
